WINDOW HOLDER

Mack Richardson, Pittsburgh, Pa.

Application November 23, 1936, Serial No. 112,366

3 Claims. (Cl. 292—70)

This invention relates to sash and casement construction for windows and counterbalances therefor and has for the primary object the provision of means which will eliminate the use of the conventional counterbalance weights and troughs therefor and permits the window casement to be constructed on a smaller scale and more economically and permit easy manual raising and lowering of the sash and will maintain the sash against accidental movement when manually released.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a front elevation illustrating a window construction in accordance with my invention.

Figure 2 is a sectional view taken on the line 2—2 of Figure 1, showing the construction of the casement and the sashes slidable therein and equipped with counterbalances.

Figure 3 is an enlarged fragmentary sectional view similar to Figure 2 showing in detail one of the counterbalances.

Figure 4 is a sectional view taken on the line 4—4 of Figure 3.

Figure 5 is a fragmentary horizontal sectional view.

Figure 6 is a detail view showing the counterbalance detached from the window sash and casement.

Figure 7 is a detail sectional view taken on the line 7—7 of Figure 6.

Referring in detail to the drawings, the numeral 1 indicates a metallic casement slidably supporting upper and lower sashes 2 and 3, the lower sash being equipped with hand grips 4 to facilitate easy manual raising and lowering of the sash. The vertical portions of the casement are of hollow formation closed by removable strips 5. The vertical hollow portions of the casement provide chambers 6 in which operate counterbalances 7 and the latter are connected to the sashes for maintaining the sashes in any of their positions and which will permit manual raising and lowering of the sashes when desired. The counterbalances 7 and their connection to the sashes are such as to require only a limited space for their accommodation therefore permitting construction of the casement 1 on a very much

smaller scale than heretofore possible when the conventional type of counterbalance weights are employed. The chambers 6 are slotted in the direction of the sashes to permit connecting of the latter with the counterbalances and so that said counterbalances may slide vertically in either direction with the vertical sliding movement of the sashes.

The counterbalances each consists of an elongated member or plate 8 and having integral therewith an angularly disposed attaching portion 9 apertured to receive screws or like fasteners for securing the plate 8 to the window sash while being mounted in the chamber 6 for sliding vertically in either direction with the sash.

The attaching portion 9 is located at one end of the plate 8 and provides to the latter a right angularly disposed wall 10. A similar wall 11 is located at the opposite edge of the plate 8 and cooperates with the portion 10 in slidably supporting

one end of a holding arm 12 which includes sections 13 and 14 pivotally connected, as shown at 15. The section 14 adjacent one end is pivoted to the plate 8, as shown at 16, and its unattached end is shaped to form a dog 17 adapted

to ride upon a serrated plate 18 secured to one wall of the chamber 6. The pivoted end of the section 13 of the holding arm 14 rides against a wall of the chamber 6 located opposite to the serrated plate 18. The serrations of the plate 18 form to the latter a series of spaced valleys in which the dog 17 engages. A pulley 19 is journaled to the section 14 of the holding arm 12 adjacent the dog 17 and a similar pulley 20 is journaled to the section 13 of the holding arm 14 adjacent the free end of said section 13.

A flexible cable or element 21 is trained over the pulleys 19 and 20 and has one end secured to the top wall of the chamber 6, as shown at 22, while the opposite end of the cable is connected to a plate 23 carrying a bolt 24 slidably mounted to a bracket 25 mounted in the chamber of the casing.

The bracket 25 is supported by a wall 26 integral with the casement and apertured to slidably receive the bolt 24 and to form in the chamber a 45 compartment 27. The bolt 24 extends into the compartment and has threaded thereto a nut 28. Interposed between the wall 26 and the nut 28 and surrounding the rod 25 is a coil spring 29

acting to place tension on the flexible element 21. The action of the spring on the flexible element may be varied by adjusting the nut on the bolt. The tension on the flexible element is sufficient to cause pivotal movement of the sections 13 and 14 of the holding arms so that they assume a po-

55

sition, as shown in Figure 6, with the dog bearing against the serrations of the plate 18 and the pivoted end of the section 13 bearing against the wall of the chamber 6 opposite to the serrated plate. The holding arm 12 is thus caused to engage with the serrated plate and the wall of the compartment will retain the sash against accidental movement in any of its positions when manually released but which will permit the sash 10 to be readily moved upwardly or downwardly manually. A guide is provided on the plate 8 to cooperate with the portions 10 and 11 in slidably supporting the section 13 of the holding arm to said plate 8. The compartment 27 of the chamber 6 is provided with a removable cover 30 so that access may be had to the compartment for the purpose of adjusting the nut on the bolt to vary the tension on the cable 21.

Having described the invention, I claim:

20 1. In combination with a window casement having a chamber and a slidable sash, a plate secured to the sash and slidable in the chamber, a holding arm pivotally and slidably connected to said plate and including pivotally connected sections each bearing against a wall of the chamber, a flexible element secured to the casement and slidably connected to the sections of the holding element, and adjustable spring means connected to the flexible element to place tension thereon and thereby effect pivotal movement to the sections of the holding arm to engage with the walls of the chamber with sufficient force to maintain the sash against accidental movement.

25 2. In combination with a window casement

having a chamber and a slidable sash, a plate secured to the sash and slidable in the chamber, a holding arm pivotally and slidably connected to said plate and including pivotally connected sections each bearing against a wall of the chamber, a flexible element secured to the casement and slidably connected to the sections of the holding element, and adjustable spring means connected to the flexible element to place tension thereon and thereby effect pivotal movement to the sections of the holding arm to engage with the walls of the chamber with sufficient force to maintain the sash against accidental movement.

3. In combination with a window casement having a chamber and a slidable sash, a plate slidable in the chamber and connected with the sash, a holding arm pivoted to the plate adjacent one end and having its opposite end slidably secured to said plate and including pivotally connected sections, one end of said arm shaped to form a dog, a serrated plate secured to a wall of the chamber to be engaged by the dog with the pivotal end of one of the sections of the arm contacting with a wall opposite to the serrated plate, pulleys secured to the sections of the holding arm, a flexible element trained over the pulleys and having one end secured to a wall of the chamber, and an adjustable spring means connected to the other end of the flexible element and carried by the casement to place the flexible element under a desired tension for effecting pivotal movement of the sections of the holding arm to bring about holding of the sash in any of its positions.

MACK RICHARDSON.
